RADIANT PANEL HEATING FOR BUILDINGS

Edward A. Milborn, Baldwin, N. Y.

Application September 5, 1946, Serial No. 694,955

1 Claim. (Cl. 257—124)

1

This invention relates to the field of radiant panel heating, which involves the heating of the floors, or ceilings of a room by the circulation of a heating fluid through a system of conduits.

It has been the practice in the past, in this field, to employ a network of intercommunicating pipes supported in grooves or embedded in concrete for carrying hot water and from which the heat diffuses, through radiant action, to warm a room. There are several disadvantages in such known panel systems, one of which is that the plaster which faces the interior of the room is not in direct contact with the pipes carrying the circulating heating medium, as a result of which the heat dissipation is not as efficient as may be desired.

The present invention overcomes these disadvantages, and provides a radiant heating panel for use in the walls, floor, or ceiling of a room composed of ducts which may be placed in intimate contact with the plaster, thus insuring most efficient heat transfer or dissipation.

Briefly stated, the heating panel of the invention comprises a pair of contacting metal sheets or plates only one of which, preferably, is deformed to form the bulging walls of a network of intercommunicating conduits. These metal plates can be made of any suitable material, such as steel, copper, brass or galvanized iron, and where the selected metal is such that there is the possibility of rusting, it may be desirable to coat the interior of the conduits or ducts with a non-rusting and non-corroding metal. The conduits are made by tightly joining the plates together, as by welding. The deformed plate is provided with means for supporting the superposed insulating material, such as plaster, in intimate association therewith, so as to enable most efficient heat dissipation into the room. This "means" may consist of spaced projections on the plate or spaced apertures therein for assuring a firm bond between metal plate and plaster. These projections may be portions of the plate which are pressed outwardly to form a design and still be continuous with the plate, or punched from the plate to form appendages which are united to the plate at their bases.

The following is a more detailed description of the invention, in conjunction with a drawing, wherein

Fig. 1 illustrates a front or side elevation view of the heating panel of the invention, before the application of plaster or other insulating material thereto;

Fig. 2 illustrates a cross-section of Fig. 1 along

the line 2—2, and shows in addition, how plaster may be firmly bonded to the panel in intimate contact therewith; and

Figs. 3 and 4 illustrate, by means of small sections of panel, a modification of the radiant heating panel of Fig. 1.

Referring to Figs. 1 and 2, the heating panel of the invention comprises a pair of metal plates 1 and 2. Plate 1 has a sinuous conduit or duct 3 terminating in an inlet 4 and an outlet 5 for the passage of heating or cooling fluid. This conduit may have other shapes, such as rectangular, or triangular, and may be formed by a suitable pressing operation. Plate 2 is flat and tightly joined to plate 1 in fluid tight relation by welding preferably at all points adjacent the bulging conduit walls 3. Points A and B in Fig. 2 indicate the preferred lines along which the welding is effected, for holding the plates firmly together and defining between them the liquid conduit or passageway.

For mounting the panel on suitable slabs or layers of insulating material 6, there are provided in both plates 1 and 2 small mounting holes 7 which register with each other and can accommodate a nail or screw of suitable size.

Plate 1 is shown provided with spaced round holes 8 and elongated slots 9 for enabling the overlying plaster layer 10 to set therein, thus assuring a firm bond and intimate contact between this plate at all points on its outer surface and the overlying plaster layer. Obviously, the apertures 8 and 9 can take other shapes and have other relative sizes and spacings, and, if desired, may register with suitable apertures, not shown, in flat plate 2 for assuring this intimate association and firm bond between panel and plaster.

Not all of the apertures 8 and 9 have been shown in Fig. 1, in order to simplify the drawing, but it should be understood that these apertures appear at different points over that surface of plate 1 which is designed to face the interior of the room to be heated, and that the apertures may or may not be symmetrically positioned.

In installing the radiant heating panel of the invention, during the construction of a building, the mounting layer of insulation 6 is first placed in position, after which the panel 1, 2 is secured to this insulation layer. Thereafter, the plaster 10 is applied to the outer surface of plate 1 in plastic form and permitted to harden or set with portions thereof firmly embedded in the apertures 8 and 9.

Fig. 3 shows an alternative form of construc-

tion for the panel of Figs. 1 and 2, differing therefrom essentially in the manner of bonding the plaster layer to the plate 1. Suitable projections 11 on metallic plate 1' replace the apertures 8 and 9 of Fig. 1. These projections 11 are in the form of straps which are punched from the plate but attached thereto at their bases. The hollow spaces between the ends of the straps enable the plaster to reach into this space and assure a firm and solid bond between plaster and plate. 10 The straps 11 thus embed themselves in the overlying plaster layer when it is setting, for assuring the firm bond and intimate contact between the panel and the plaster. Except for this difference, the construction of the panel of Fig. 3 15 is the same as that of Fig. 1.

Fig. 4 shows still another form of construction in which outwardly pressed diamond-shaped portions 12 are utilized to insure the firm bond between the metallic plate 1'' and the overlying 20 plastic layer. Obviously, these projecting portions may take a variety of configurations.

What is claimed is:

For use in a radiant heating system, a panel 25 designed for concealed use behind a wall, floor or ceiling of a room, said panel comprising a pair of plates firmly joined together in fluid tight re-

lation, at least one of said plates being deformed to produce a network of intercommunicating conduits, one of said plates having punched out straps integral therewith at both ends for supporting on said one plate in direct contact with the entire outer surface thereof a layer of plaster, said straps having hollow spaces between said ends to enable said plaster to enter therein while in a plastic state.
